(Cl. D26—5)

To all whom it may concern:

Be it known that I, William P. Lear, a citizen of the United States of America, residing at No. Hollywood, in the county of Los Angeles, in the State of California, have invented a new, original, and ornamental Design for a Combined Electric Motor and Manually Operated Drive Unit, of which the following is a specification, reference being had to the accompanying drawings a part hereof.

In the drawings:

Fig. 1 is a perspective view of a combined elec-

tric motor and manually operated drive unit showing my new design;

Fig. 2 is a top plan view;

Fig. 3 is a side elevational view;

Fig. 4 is a left end elevational view; and

Fig. 5 is a right end elevational view thereof.

I claim:

The ornamental design for a combined electric motor and manually operated drive unit, substantially as shown.

WILLIAM P. LEAR.
